REFRIGERATOR

George E. Curtiss, Jr., Penn Wynne, Pa., assignor
to Philco Corporation, Philadelphia, Pa., a cor-
poration of Pennsylvania

Application November 16, 1943, Serial No. 510,547

7 Claims. (Cl. 20—68)

1

The present invention relates to refrigerators, and more particularly to an improved door structure and operating means therefor.

It has heretofore been proposed to use a slideable door instead of the swinging door commonly mounted on a refrigerator cabinet for closing and opening the food storage compartment thereof. However, the use of a slideable door for the purpose stated has met with numerous problems because of the difficulties experienced in effecting a proper seal between the door and adjoining portions of the cabinet walls while allowing for free sliding movement of the door.

The principal object, therefore, of the present invention is to provide a refrigerator cabinet having a slideable door capable, when in closed position, of effectively sealing the refrigerated area with which it is associated and adapted, when moved to and from opened or closed position, to slide freely in a guided path along the associated walls of the cabinet structure.

It is also an important object of the invention to provide a refrigerator cabinet with a door mounted for sliding movement thereon and having displaceable sealing means and movable handle means, the sealing means being located for snug engagement with adjoining portions of the refrigerator cabinet structure and operatively connected with the handle means whereby actuation of the latter in a general direction to open the door displaces the sealing means to disengage the same from said portions of the cabinet structure, thereby freeing the door for unimpeded sliding movement.

Another important object of the invention resides in the provision of a slideable door for a refrigerator cabinet having a sealing gasket displaceably mounted thereon for forceful application against adjoining wall portions of the cabinet structure to effect an air tight seal therebetween when and only when the door is in its fully closed position.

Still another important object of the invention resides in the provision of a slideable door for a refrigerator cabinet having a displaceable sealing gasket mounted thereon for movement into and out of contact with adjoining wall portions of the cabinet structure, and adapted to be moved out of contact with the cabinet wall portions when it is intended to slide the door to its open position but prior to the actual sliding of the door to said opening position.

The invention is further characterized by the provision of a slideable refrigerator door of the character mentioned adapted normally to be urged to closing position but capable of being maintained in various partially opened positions if desired.

Other important objects and characteristic features of the invention will be apparent to those skilled in the art from the following de-

2

scription based upon the accompanying drawings in which:

Figure 1 is a perspective view of a refrigerator cabinet provided with a slideable door constructed in accordance with this invention and illustrating said door in fully closed position;

Figure 2 is a view similar to Figure 1 illustrating the slideable door in fully opened position;

Figure 3 is a transverse vertical section on a reduced scale taken through the height of the refrigerator cabinet;

Figure 4 is a sectional view taken longitudinally through a portion of the door and lower section of the cabinet and looking in the general direction indicated by the arrows 4—4, Figure 3;

Figure 5 is an enlarged elevational cross-sectional detail of the counter-balancing device associated with the door and taken substantially along line 5—5, Figure 3;

Figure 6 is an enlarged cross-sectional detail looking in the general direction indicated by arrows 6—6, Figure 1;

Figure 7 is a reduced sectional elevational view looking in the general direction of arrow 7—7,

Figure 6 and illustrating one embodiment of the means cooperating with the door to maintain the same at points intermediate its fully closed and fully opened positions;

Figure 8 is a perspective view of the door handle assembly;

Figure 9 is a transverse vertical section through the refrigerator door viewed from the line 9—9, Figure 6; and

Figure 10 is a view similar to Figure 9 but taken substantially at right angles thereto as indicated by arrows 10—10, Figure 9.

Referring now more particularly to the drawings, there is shown a refrigerator cabinet 1 which may have the usual rectangular configuration and the usual construction including relatively spaced inner and outer liners 2 and 3, respectively, said liners being joined by means of a suitable breaker strip 4 conveniently covered with a finishing strip 5 (Figure 6).

The cabinet 1 may be, and preferably is, provided with a lower section 6 and an upper section 7. The lower section 6 preferably constitutes the housing portion for the motor-compressor unit (not shown) of an ordinary primary refrigerating system, whereas the upper section

7 preferably constitutes the refrigerated portion of the cabinet and, for that purpose, is insulated as indicated at 8 according to the usual practice. The upper section 7, moreover, may be divided by means of an insulated wall 9 into two superposed compartments 10 and 11, respectively.

The uppermost compartment 10 preferably forms a low temperature freezing chamber in which the primary evaporator 12 of usual well-known type may be mounted, while the remaining compartment 11 preferably forms a food storage chamber which may be refrigerated by means of a

closed secondary system 13, associated with the inner liner 2 defining said chamber. Shelves 14 are conveniently mounted at fixed spaced points within the compartment 11 for the storage of food therein.

The uppermost compartment 10 opens at the front and is adapted to be closed by means of a door 15 preferably hinged at the top as indicated at 16 and provided with a handle 17 at the lower edge portion so that said door 15 may be swung upwardly to give clear access to the associated compartment 10. In closed position, the door 15 preferably fits between those portions of the cabinet side walls which lie adjacent to sides of said door, and nests within a recess 18 formed in a forwardly extended portion 19 of the insulated dividing wall 9 in the manner more clearly shown in Figure 4. Sealing gasket means 20 is interposed between contacting surfaces of said door 15 and walls defining the open front of the compartment 10, thus effectively sealing the latter.

In accordance with the present invention, the open front of the food storage compartment 11 is adapted to be closed by means of a vertically slideable door 21 which preferably is of substantially rectangular configuration and has a width and thickness to fit freely within the confines of an area outlined by the forwardly projecting edge portions of the side walls of the cabinet 1, by the underside of the forwardly extended portion of the dividing wall 9 and by the forward face of the floor of the compartment 11, as more fully shown in Figures 1, 2 and 6. As more clearly appears in Figure 3 of the drawings, the door 21 is of a height in excess to the height of its associated compartment 11 so that said door, in its closed position, extends from the underside of the forwardly extended portion 19 of the dividing wall 9 to a point substantially level with the bottom surface of the floor of compartment 11. In practice and as illustrated in Figure 6, the door 21 includes relatively spaced inner and outer panels 22 and 23, respectively, between which is packed insulating material 24.

The door 21 is adapted to slide vertically to and from closing and opening positions and for that purpose, said door is preferably provided with rollers 25 disposed to ride in guide track members 26 suitably arranged in the corresponding forwardly projecting portions of the cabinet walls. Moreover, the door 21 is normally urged towards and maintained in its closed position by actuation of a counterbalancing mechanism 27 which preferably comprises pairs of articulated levers 28 and 29 and force reacting means 30 associated therewith to counteract the weight of the door and tend to lift the same.

As shown in the drawings and particularly Figures 3 and 4 thereof, the free end of one lever 28 of each pair is pivotally connected as at 31 to the lower edge portion of the door 21 whereas the free end of the other lever 29 of each pair is pivotally connected as at 32 to the floor of the cabinet lower section 6. As shown in Figure 5, the interconnected ends of said levers may be formed to provide bearing portions 33 for a spindle member 34 with which the force reacting means 30 is associated, said means, in this instance, consisting of a spiral spring having one end attached to said spindle member 34 by means of a clamp arrangement and lock screw 36, and the other end attached to one of the bearing forming portions 33 of the levers as indicated at 37.

It is to be noted that in practice the winding of the spiral spring 30 is such that a continuous

force is applied to the door 21 in a direction to urge the same to its closing position and that this force increases as the door is lowered towards its opened position. However, it is also to be noted that the arrangement is such that when the door 21 is in its fully opened position, that is, the position indicated in dotted lines in Figure 3 of the drawings, the force stored in the spring 30 is static but this force is released the instant the door is started in its upward movement. In order that the door 21 may readily be lowered towards its opening position and be given its initial upward movement towards its closing position, there is provided a handle 38 located centrally of the door at the upper marginal edge portion thereof and mounted thereon in a special manner to be described presently.

It will be understood that when the door 21 is in closed position, an adequate air tight seal must be effected between said door and the surrounding adjoining surfaces of the cabinet structure if the associated refrigerated compartment 11 is to be kept at its highest possible degree of efficiency, but that when it is desired to move the door towards open position, said seal must be such that its frictional pressure against the door be fully relieved if the latter is to slide freely and unobstructedly.

For this purpose, there is mounted on each side 30 of the door and suitably anchored on the opposed side edges of the inner and outer panels 22 and 23 thereof, resilient gasket strips such as shown at 39 in Figures 6 and 10. Each gasket strip 39 has a generally W-shaped cross-sectional configuration, the intermediate resilient portion 39a of which is adapted to effect the seal and is fixedly associated with a substantially T-shaped bar 40 extending, as shown in Figure 10, throughout the length of said gasket strip. By reason of this construction, it will be understood that movement of the bars 40 in a plane substantially at right angles to those surfaces of the forwardly projecting edge portions of the cabinet side walls which lie adjacent the gasket strip carrying edges 45 of the door, will bring said seal effecting portion 39a of the respective gasket strip 39 into and out of contact with the corresponding surface of the mentioned cabinet wall portions in the manner illustrated in full and dotted lines in Figure 10.

According to the present invention, this movement of the bars 40 is controlled by the actuation of a toggle mechanism 41 which preferably is constructed as shown in Figures 6, 8, 9 and 10, wherein the toggle mechanism 41 includes pairs 55 of articulated arms 42 and 43, the arms 42 being pivotally attached to the opposed end portions of the bars 40 and the arms 43 being pivotally attached to the upper and lower brackets 44 and 45 respectively mounted within the door 21 at fixed points at the top and bottom portions thereof. The pairs of articulated arms 42 and 43 on each side of the door, are interconnected by means of links such as that shown at 46, in Figures 9 and 10, so that the movement of one pair of arms is transmitted to the corresponding pair of arms. As clearly illustrated in said Figures 9 and 10, the interconnected pairs of articulated arms 42 and 43 normally are urged and maintained into extended relationship by action of springs, such as 47, which abut a rigid extension 48 formed with each lower bracket 45 and press downwardly against a stop 49 on the corresponding link 46. In this manner the bars 40 normally are urged into the position shown 75 in full lines in Figure 10 of the drawings.

In accordance with this invention, the breaking of the toggle mechanism to cause retraction of the arms 42 and 43 and accordingly effect the withdrawal of the bars 40 as indicated by the dotted lines in Figure 10, is accomplished through the initial manipulation of the handle 38 in its door opening direction. For this purpose, the handle 38 is formed with extensions 49 passing through elongated slots 50 in the door outer panel 23 and fixed to the intermediate portion of a torque rod 51 having its opposite end portions 52 extended and shaped to engage a pin 53 projecting from the point of interconnection between the articulated arms 42 and 43 of the toggle mechanism 41. The torque rod 51 is rotatably supported in bearings 54 formed with the upper brackets 44 and also in bearings 54a on a support member 55 which is provided with elongated slots 56 registering with the slots 50 in the door outer panel for accommodating the handle extensions 49. The support member 55 may be of any suitable construction.

From the foregoing description, it will be understood that when the door 21 is in its fully closed position, the sealing portions 39a of the gasket strips 39 are forced, by action of the springs 47 on the toggle mechanism 41, against the adjacent surfaces of the cabinet sidewall portions thereby establishing an air tight seal therebetween. However, when it is desired to open the door 21, initial manipulation of the handle 38 in downward direction as indicated by arrow A in Figure 8 rotates the torque rod 51 in the direction of arrow B thus raising the extended end portions 52 thereof and accordingly exerting an upward force on the pin 53 as represented by arrow C which causes the toggle mechanism 41 to assume the position shown in dotted line in Figure 10 thereby withdrawing the bars 40 and retracting the sealing portions 39a of the gasket strips 39 away from the corresponding wall portions so that the door becomes free to slide in its guided path of movement.

In order that the gasket strips 39 may be maintained in retracted position against the normal action of the springs 47 when the door 21 is in fully opened or in partially opened positions, there are provided locking devices such as that shown at 57, each preferably consisting of a spring pressed dog 58 pivotally carried by the lower bracket 45 of the toggle mechanism 41 and disposed for engagement within a notch 59 cut in one of the associated articulated toggle arms. The spring pressed dogs 58 are normally urged into position for engagement with the associated arms 42 of the toggle mechanism, but are held out of said position when the door is in fully closed position by means of a strike plate 60 arranged on the cabinet structure to cause movement of the dogs in opposition to their normal spring pressed action for positioning out of engagement with the toggle mechanism as the door 21 reaches its fully closed position. Because of this arrangement, it will be appreciated that the door 21, when in open position, is always free to slide either up or down and, upon reaching its fully closed position, the toggle mechanism is released whereupon the gasket strips 39 are forced against the adjoining surfaces of the cabinet sides thus sealing the opening of the food compartment 11 and frictionally holding the door against sliding movement.

When the door 21 is in its fully closed position, the top and bottom of the opening aforesaid are

sealed by means of gasket strips 61 and 62, one gasket strip 61 being carried preferably by the underside of the dividing wall 8 so that the top edge of the door snugly presses against said strip, whereas the other gasket strip 62 is carried by a ledge 63 at the bottom edge of the door to press against the bottom of the storage compartment floor.

In accordance with the invention, means may be provided to hold the door at various shelf levels thereby making it unnecessary to open the door to its full extent when access to the uppermost shelves only is desired. For this purpose, depressable stop elements, such as shown at 64 in Figure 7, may be mounted on the track members 26 at fixed points in relation to the shelves 14 and to the rollers 25 on the upper side portions of the door, so that said elements will engage the mentioned rollers when the door is opened to the desired shelf level and maintain the door at said level against the action of the counterbalancing mechanism 27. It is to be noted that the depressable stop elements 64 are such that while they will maintain the door at the desired shelf level if the door is lowered to a point where the rollers 25 pass said elements and then is slowly lifted until the rollers gently contact the elements, said elements 64 will be depressed by the rollers 25 when the door is moved unrestricted under full force of the counterbalancing mechanism 27 so that said elements do not interfere with the normal operation of the door in its movement towards fully closed position by action of said counterbalancing mechanism. It is also to be noted that when the door is held at shelf level by the elements 64, a slight uplifting urge on the handle 38 is all that is necessary to cause the rollers 25 to depress said elements and thus free the door for its movement towards closing position.

It is known that heretofore it has been suggested to provide gasket means displaceably mounted on portions of a refrigerator cabinet and engageable with a slideable refrigerator door having means adapted to force the gasket means away from the door when actually moving towards opened position and to release the gasket means for its engagement with the door as the latter is moving towards closed position. Such an arrangement, however, necessitates movement of the door itself before displacement of the gasket means occurs, so that the gasket means in fact resist free initial movement of the door towards opened position and free final movement of the door to closed position. Therefore, it is believed that the present invention is the first to provide an arrangement operable to cause the sealing gasket to be moved completely free of the door prior to its initial opening movement and particularly an arrangement where movement of the sealing gasket to free the door is accomplished by initial actuation of a handle operable to open the door.

Whereas specific embodiments of the various mechanisms have been shown and described herein, it is to be understood that such embodiments are capable of modification within the scope of the claims without departing from the invention.

I claim:

1. In a refrigerator, a cabinet structure provided with a refrigerated compartment having an open side, a door mounted on the cabinet and arranged in the open side of said compartment for sliding movement to and from open and closed

positions, gasket means between said door and adjacent portions of the cabinet structure for sealing said compartment, mechanism operable to move the gasket means out of sealing position prior to movement of the door toward open position, and means actuated by movement of the door to closed position for moving the gasket means into sealing position.

2. In a refrigerator, a cabinet structure provided with a refrigerated compartment having an open side, a door mounted on the cabinet and arranged in the open side of said compartment for sliding movement to and from open and closed positions, gasket means between said door and adjacent portions of the cabinet structure movable into position for sealing said compartment, mechanism for retracting the gasket from the said sealing position prior to movement of the door from closed position, means for retaining the gasket in the retracted position while the door is open, and means for rendering the retaining means inoperative when the door is closed.

3. In a refrigerator, a cabinet structure provided with a refrigerated compartment having an open side, a door mounted on the cabinet and arranged in the open side of said compartment for sliding movement to and from open and closed positions, retractable gasket means carried by said door and disposed for engagement with portions of the cabinet structure for sealing said compartment, and mechanism connected with said gasket means and operable to urge and maintain the same in sealing engagement with said cabinet portions in response to movement of the door into closed position and including means for retracting said gasket means from sealing engagement with said cabinet portions prior to movement of the door toward open position.

4. In a refrigerator, a cabinet structure provided with a refrigerated compartment having an open side, a door mounted on the cabinet and arranged in the open side of said compartment for sliding movement to and from open and closed positions, a handle movably mounted on the door for manually sliding the same, retractable gasket means carried by said door and disposed for engagement with portions of the cabinet structure for sealing said compartment, mechanism connected with said gasket means and with said handle operable to urge and maintain said gasket means in sealing engagement with said cabinet portions when the door is moved into closed position and actuatable through the medium of said handle to retract said gasket means from sealing engagement with said cabinet portions prior to sliding of the door toward open position, and means operative independently of the handle for retaining the gasket means in the retracted position when the door is open.

5. In a refrigerator, a cabinet structure provided with a refrigerated compartment having an open side, a door mounted on the cabinet and arranged in the open side of said compartment for sliding movement to and from open and closed positions, retractable gasket means carried by said door and disposed for engagement with portions of the cabinet structure for sealing said compartment, mechanism connected with said gasket means operable in response to movement of the door into closed position to urge and maintain the gasket means in sealing engagement with said cabinet portions, and means for manually actuating said mechanism to retract

7
said gasket means from sealing engagement with said cabinet portions prior to movement of the door toward open position.

6. In a refrigerator, a cabinet structure provided with a refrigerated compartment having an open side, a door mounted on the cabinet and arranged in the open side of said compartment for sliding movement to and from open and closed positions, retractable gasket means carried by said door and disposed for engagement with portions of the cabinet structure for sealing said compartment, and mechanism connected with said gasket means operable to urge and maintain the same in sealing engagement with said cabinet portions when the door is moved into closed position and to retract said gasket means from sealing engagement with said cabinet portions prior to movement of the door toward open position, said mechanism including a toggle assembly connected with the gasket means, means acting on said toggle assembly to hold the same in extended position for forcing the gasket means into the said sealing position, means acting upon said toggle assembly to move the same to retracted position against the action of said last mentioned means to thereby withdraw the gasket means from the sealing position and to free the door for sliding movement, and locking means mounted for engagement with the toggle assembly to releasably lock the same in its retracted position.

7. In a refrigerator, a cabinet structure provided with a refrigerated compartment having an open side, a door mounted on the cabinet and arranged in the open side of said compartment for sliding movement to and from open and closed positions, retractable gasket means carried by said door and disposed for engagement with portions of the cabinet structure for sealing said compartment, and mechanism connected with said gasket means operable to urge and maintain the same in sealing engagement with said cabinet portions when the door is moved into closed position and to retract said gasket means from sealing engagement with said cabinet portions prior to movement of the door toward open position, said mechanism including a toggle assembly connected with the gasket means, means acting on said toggle assembly to hold the same in extended position for forcing the gasket means into its sealing position, means acting upon said toggle assembly to move the same to retracted position against the action of said last mentioned means to thereby withdraw the gasket means from its sealing position thereby freeing the door for sliding movement, locking means mounted for engagement with the toggle assembly to lock the same in retracted position, and means disposed to disengage said locking means from the toggle assembly when the door moves to the fully closed position.
